UNITED STATES PATENT OFFICE.

JOHN H. BERGHAUS, JR., OF LOUISVILLE, KENTUCKY.

SAFETY DEVICE FOR ELEVATORS.

1,384,378.

Specification of Letters Patent. Patented July 12, 1921.

Application filed February 16, 1920. Serial No. 358,849.

To all whom it may concern:

Be it known that I, JOHN H. BERGHAUS, Jr., a citizen of the United States, residing at Louisville, county of Jefferson, and State 5 of Kentucky, have invented a new and useful Safety Device for Elevators, of which the following is a specification.

This invention relates to safety devices for elevators.

10 An object of the invention is to provide means for preventing accidents in the operation of elevators, more especially such as are due to an object, as the foot of an operator, projecting beyond the edge of the elevator, 15 and being caught between the floor of the elevator and the ceiling of the room, as the elevator ascends.

With the foregoing and other objects in view, the invention consists of the novel 20 construction and arrangement of parts illustrated in the accompanying drawing, which forms a part of this specification, wherein is set forth an embodiment of the invention, but it is to be understood that such changes 25 and modifications may be resorted to as come within the scope of the appended claims.

In the drawing, wherein similar reference 30 characters designate like parts in the several views, Figure 1, is a perspective view of a portion of an elevator equipped with an embodiment of the invention; and Fig. 2, a section on line 2-2 of Fig. 1.

Referring now in detail to the drawing, the reference character —10— designates 35 one of a pair of vertical timbers, of which one is positioned on each side of an elevator shaft which extends upward through openings, or hatchways —11— in floors —12— and extends the full height of the building.

40 A car —13— which comprises a platform —14—, side posts —15— and a head beam —16— is raised and lowered by suitable means such as a rope —17— attached to the head beam. Shoes —18— on the posts 15, 45 bear against the sides of guide rails —19— which are secured to the vertical timbers. The car is usually closed in on three sides by a railing or wall —20—, thereby permitting access thereto from one side only. A 50 wing —21— is pivotally suspended by suitable means such as hinges —22— at the

lower edge of each floor opening on the side thereof toward which the car opens. The wings are suspended from the ceiling or from a joist of each floor and in such relationship to the hatchway that when in actuated position its inner face will lie in substantially the same vertical plane as the side —23— of the hatchway, and it may extend the full width of the hatchway, or only such 55 a part thereof as corresponds to the opening from the car. Normally the wing is biased by suitable means such as a spring —24—, so that it stands at an angle to the elevator shaft with its lower edge spaced from the 60 opening. A sliding bar —26— is connected by one end to a stud —27— extended from an end of the wing. The bar extends through a slot —28— in the vertical timber 65 and is bent at an angle so that a roller —29— 70 on its inner end lies in the path of a cam block —30— positioned on the post, 15, of the elevator, the arrangement being such that as the platform in its upward travel approaches an opening, the cam 30 will engage the roller on bar 26, shifting it longitudinally and drawing the wing to which it is connected down flush with the side of the 75 hatchway. The wing as it is drawn down will push before it anything that may project over the edge of the platform, such as the operator's foot, thereby preventing it from being injured by being caught between 80 the platform and the edge of the opening.

Having thus described my invention so 85 that those skilled in the art pertaining thereto can make and use the same,

I claim:

1. In combination a floor, having an opening, an elevator guide at the side of said opening, an elevator movable through the opening, a wing pendent below said floor in a plane substantially the same as a side of said opening, means normally biasing the lower edge of said wing away from the 90 opening, a bar pivoted to said wing and extending through the elevator guide, and means on the elevator to move said bar against the action of said biasing means.

2. In combination, a floor having an opening, an elevator guide at the side of said opening, an elevator movable through the 100

opening and having an upright member slide-
able on said guide, a wing pending below
said floor in a plane substantially that of
the side of the opening, a spring normally
holding the lower edge of said wing away
from the opening, a bar pivoted to said wing
and extending through the elevator guide,

a roller carried on the portion of the bar
projecting through said guide, and a cam
on the elevator upright arranged to engage 10
the roller and move the bar and wing as the
elevator passes upward.

JOHN H. BERGHAUS, JR.
